US00D823324S

(12) **United States Design Patent** (10) Patent No.: **US D823,324 S**
 McGinn-Straub et al. (45) Date of Patent: ** Jul. 17, 2018

- (54) **DISPLAY SCREEN FOR GLYCAN ANALYZER WITH GRAPHICAL USER INTERFACE**
- (71) Applicant: **LIFE TECHNOLOGIES CORPORATION**, Carlsbad, CA (US)
- (72) Inventors: **Wesley McGinn-Straub**, Morgan Hill, CA (US); **Baburaj Kunnummal**, Fremont, CA (US); **Mahesh Nalkande**, Foster City, CA (US); **Mandar Dhole**, Maharashtra (IN); **Sakshi Rao**, Maharashtra (IN); **Rameez Choudhari**, Maharashtra (IN)
- (73) Assignee: **Life Technologies Corporation**, Carlsbad, CA (US)
- (**) Term: **15 Years**
- (21) Appl. No.: **29/548,421**
- (22) Filed: **Dec. 14, 2015**
- (51) LOC (11) Cl. **14-04**
- (52) U.S. Cl. **USPC** **D14/486**
- (58) **Field of Classification Search**
 USPC D14/485-495

Assistant Examiner — Rachel Voorhies

(57) **CLAIM**

The ornamental design for a display screen for glycan analyzer with graphical user interface, as shown and described.

DESCRIPTION

The FIGURE is a view of an embodiment of a display screen for glycan analyzer with graphical user interface of our new design.

The broken line perimeter illustrates a display screen and forms no part of the claimed design. The inner broken line showing illustrates portions of the graphical user interface that form no part of the claimed design.

1 Claim, 1 Drawing Sheet
